DESIGN FOR A BEDSPREAD

Louis J. Freeman, New York, N. Y.

Application February 26, 1943, Serial No. 109,635

Term of patent 3½ years

To all whom it may concern:

Be it known that I, Louis J. Freeman, a citizen of the United States of America, residing in New York city, county of New York, and State of New York, have invented a new, original, and ornamental Design for a Bedspread, of which the following is a specification, reference being had to the accompanying drawing, forming part thereof, wherein the figure of the drawing is a plan view of a bedspread showing my new design.

The characteristic feature of my new design resides in the combination on the bedspread disclosed of the chenille center and fringed outer edges, as shown.

I claim:

The ornamental design for a bedspread, substantially as shown and described.

LOUIS J. FREEMAN.
